UNITED STATES PATENT OFFICE

2,325,653

WALL CONSTRUCTION

William A. Bingham, Euclid, Ohio

Application February 8, 1941, Serial No. 378,079

3 Claims. (Cl. 72—107)

My invention relates to building construction and more particularly to means for spacing structural units in a wall and sealing and insulating the spaces against the infiltration of moisture or other undesirable elements.

One of the objects of my invention consists in the provision of a spacer element adapted to be so placed between adjacent walls of adjacent blocks, tiles or the like in a wall construction that moisture will be prevented from passing through the wall and that said element will provide additional bearing areas between the blocks.

Another object is to provide spacing elements of the above named character which will provide a seal between the outer adjacent walls of adjacent units or blocks to prevent the seepage of moisture through the wall and to prevent an excess of bonding mortar or cement from passing inwardly of the block faces sufficiently to drop into the voids or air cells within the block structure while at the same time not impairing the quality of the bond of the cement with the blocks between which it is applied.

A further object of the invention consists in the provision of a spacer and sealing member for the purposes specified which is preferably in the form of an elongated strip or sheet and which can be provided in convenient workable lengths.

Another object is to provide means connecting a plurality of these spacing members in such a way that the members can readily be shifted longitudinally with respect to each other to obtain a desired spacing of the elements laterally.

Other objects and advantages of my invention will become more apparent as the following description of an embodiment thereof progresses, reference being made to the accompanying drawing in which like reference characters are employed to designate like parts throughout the same.

In the drawing:

Figure 1 is a perspective view of a block or tile wall section in which several courses of blocks are shown and in which my invention is illustrated applied in use;

Figure 2 is a plan view of a pair of spacer unit lengths spaced apart in parallel relation;

Figure 3 is a view similar to that of Figure 2 illustrating the manner in which the spacer elements may be shifted longitudinally to alter their relationship laterally;

Figure 4 is a transverse section taken on line 4—4 of Figure 2; and

Figure 5 is a view similar to that of Figure 4

showing a slight modification in the application of the spacing wires between the sealing elements.

One of the problems in block wall construction is to prevent the seepage of water and moisture through the wall. This usually occurs along the cement bonds both between courses of blocks or tiles and between blocks of the same course. Another disadvantage which is usually present is the fact that in the application of the cement between adjacent block or tile faces some of the cement drops into the voids or air cells formed in the hollow tile or blocks, oftentimes in relatively large quantities especially after a number of courses of block have been laid.

My invention is intended to eliminate these disadvantages and at the same time to provide a simple and low cost means easily applied which will be an effective seal against moisture between the blocks of each course and between each of the courses in the wall. Furthermore by means of my invention, the use of mortar or cement in the bonds will be more efficient and less wasteful.

In carrying out my invention a sealing strip or elongated sheet 1 of material impervious to moisture is provided in convenient lengths which can be cut transversely when necessary at the end of a wall section. The strips are preferably laid end to end along the upper surface of the blocks of a course as indicated in Figure 1, one strip being placed inwardly of and parallel to one face of the blocks and another strip being placed inwardly of and parallel to the other face of the blocks in the course. These strips are of sufficient thickness that when the blocks of the next course are set thereon in proper relation to the course below a bonding space 2 is provided longitudinally between the courses to receive the bonding cement or mortar 3.

The spacing strips or elongated sheets 1 may be made of any suitable material impervious to water and which possesses some compressibility under the normal load imposed upon it. I have found that asphaltated felt is extremely satisfactory for the purposes of my invention and also for the reason that it is not expensive to manufacture. Other materials such as impregnated cork or a compound of asbestos fibers and asphalt are also highly efficient and desirable.

I have illustrated in Figure 1, in separate courses, the manner of applying my invention to two types of block construction.

In courses indicated by the blocks 4 and 5 it will be noted that the ends of the individual blocks are provided with vertical ribs 6 which abut

the respective ribs formed on the ends of adjacent blocks thus providing a vertical bonding recess 6' for receiving the bonding material in the usual manner. Between the courses 4 and 5 I provide a pair of spacer strips 1 in accordance with my invention. Each spacer strip runs parallel to the block face and is preferably placed as shown a short distance inwardly of each face to provide a space 2 for receiving the bonding material. The strips 1 are spaced laterally by means of the spacing rods or wires 1 which are bendable at 8 so as to permit longitudinal adjustment of the strips relative to each other to obtain the desired lateral spacing of these strips. This is illustrated more clearly in Figure 3 although a close examination of the spacer strips in Figure 1 between the courses 4 and 5 will reveal that they have been adjusted longitudinally slightly to provide the proper lateral spacing of the strips.

The blocks in courses 9 and 10 are of the second type, that is, the block end structure is provided with flat end faces 11. Where blocks of this type are employed, it is desirable to use my invention as shown at 12-12. The same strip or sheet material may be used when cut to proper length, as illustrated, to provide a seal between the ends of adjacent blocks in a course.

The strips are placed in an upright position, part of each strip overlying a portion of each end face 11 inwardly of the outer faces of the block and extending inwardly into the set back portion 13 of the block end. Longitudinal sealing strips 1 are provided between courses of blocks as described above.

Thus it will be seen that as the blocks of a course are set, spaces 14 are provided for receiving bonding cement between the spaced ends of adjacent blocks and that longitudinal spaces are provided between the courses to receive bonding cement at 3.

Two methods of attaching the spacing wires or rods 1 to the strips may be employed. As shown in Figures 1 to 4 inclusive, the ends of the wires are embedded in the side walls of the strips 1. In Figure 5 a slight modification is shown in which the wires 1 lie in a plane out of but parallel to the plane of the spaced strips, the ends of the wires being bent inwardly and embedded in one of the faces of the respective strips. In this latter form, the spacing of the strips laterally can be adjusted without further bending the wires, the inturned ends 15 of the wires serving

as pins or pivots in shifting the strips longitudinally.

My invention therefore provides a simple inexpensive means for spacing courses and/or units of a course to provide a recess for receiving the bonding material, at the same time, providing an effective seal along the bond areas against the passage of moisture through the wall. Furthermore, the setting back of the strips from the block face provides additional bearing areas for the assembled blocks.

Another advantage obtained by the use of my invention is that the block units of a wall may be set in place in several courses, the spacing and insulating strips being positioned as shown in Figure 1, and the cement or mortar applied subsequently. This procedure permits a wall to be quickly set up in inclement weather whereas the cement 3 need not be applied to the channels 2 until conditions are suitable.

Various changes may be made in the details of construction and arrangement of parts without departing from the spirit of the invention or the scope of the appended claims.

I claim:

1. In a block or tile wall construction comprising a plurality of courses of block and tile units arranged in end to end relation in each course, spacing means interposed between adjacent courses, said spacing means comprising substantially parallel members spaced apart laterally and means connecting said parallel members and angularly movable with respect to said parallel members upon relative movement of said members longitudinally to effect a lateral spacing adjustment of said members.

2. A spacing and sealing device for wall constructions comprising a pair of substantially parallel strips of water repellent material, and bendable means connecting said strips laterally whereby upon relative movement of said strips longitudinally lateral spacing thereof may be altered.

3. A spacing and sealing device for wall construction comprising a pair of substantially parallel strips of water repellent material, and spacing means connecting said strips laterally, said spacing means comprising rigid members pivotally connecting said strips whereby said strips may be disposed in any one of a plurality of parallel spaced positions.

WILLIAM A. BINGHAM.
